DRINKING TROUGH FOR POULTRY

David Christopher Leeming, Hill House, 22a Bereweke
Ave., Winchester, England

Filed May 5, 1969, Ser. No. 17,019

Claims priority, application Great Britain Dec. 4, 1968

Term of patent 14 years

Int. Cl. D30—02

U.S. Cl. D30—16

Fig. 2.

Fig. 3.

FIG. 1 is a perspective view from above of the drinking trough showing my new design;

FIG. 2 is an underside plan view thereof;

FIG. 3 is a top plan view thereof;

FIG. 4 is a section along the line 4—4 of FIG. 3.

I claim:

The ornamental design for a drinking trough for poultry, substantially as shown.
